UNITED STATES PATENT OFFICE.

WILLIAM C. CROSS, OF BOSTON, MASSACHUSETTS.

PAPER-BAG MACHINE.

SPECIFICATION forming part of Letters Patent No. 244,860, dated July 26, 1881.

Application filed June 27, 1881. (No model.)

To all whom it may concern:

Be it known that I, WILLIAM C. CROSS, of Boston, Massachusetts, have invented certain new and useful Improvements in Machines for Making Paper Bags, of which the following is a specification.

My invention relates to machines for making satchel-bottom paper bags. It consists in a certain improvement in the construction and arrangement of the devices for making the first or diamond fold, which will be hereinafter specifically pointed out.

It also consists in the hereinafter-described combination of instrumentalities, whereby I unfold and straighten out the completed bag at the point where a blind fold in the bag-body is in some paper-bag machines formed at the time the final fold of the satchel-bottom is made.

The nature of my invention and the manner in which the same is or may be carried into effect will be understood by reference to the accompanying drawings, in which—

Figure 1 is a side elevation of so much of a satchel-bottom paper-bag machine as is needed to illustrate my invention. Fig. 2 is a sectional view, on an enlarged scale, of a portion of the diamond-fold-forming rolls. Fig. 3 is a plan of the portion of one of said rolls.

I have not deemed it necessary to show the mechanisms for forming and pasting the flattened paper tube, for severing the same into bag-lengths, and for feeding the blanks thus produced to the folding instrumentalities. Said mechanisms may be of any approved kind.

For the purpose of making the diamond-fold on the flattened tubular bag-blank I make use of rotating diamond-fold-forming rolls A, which I now proceed to describe: Said rolls are provided with nippers a, which take hold of the plies of the blank passing between them, and hold them for a certain period upon the moving diverging surfaces of the rolls, thus spreading wide open the mouth end of the blank and putting it in condition to have the diamond-fold completed by passage of the blank between the lower nipper-roll (on which it is retained by the nipper of that roll after it has been released by the other) and the upper one of the pair of power-driven rolls B, which, as indicated in Fig. 1, carry along the diamond-folded blank to the subsequent folding devices.

It is not new with me to form the diamond-

fold by the conjoint action of two diverging surfaces, nor is it broadly new to use nippers or other instrumentalities for the purpose of holding the plies on said surfaces; but there is novelty in the particular arrangement shown by me for this purpose.

The nipper-rolls are formed each with a central shallow peripheral groove, b, intended to accommodate the light metallic spring opening fingers or strips c, which extend from the trunk or former C between the rolls to a point just beyond their bite, as shown in Fig. 2. These fingers at their free ends have a tendency to spread apart, so that they will open the mouth end of the blank.

In suitable recesses or pockets a' in the rolls are mounted on rock-shafts a² the nippers a, which are so placed that at one extreme of their movement (the movement in said direction being due to adjustable cams a³ fixed on the main frame, over which run the crank-arms a⁴ of shafts a²) they will be contained in the recesses a', and at their other extreme of movement (movement in this direction being induced by the usual spring or springs when the nippers are released from the contact of their cams) their jaws or acting ends will overlap the edges of the recesses a' and rest on the bottom of the shallow grooves b, as shown in the drawings. The nippers are so timed that they close, soon after they pass beyond the bite of the rolls, at a time when the mouth end of the blank x has just emerged from between the rolls and is opened by the spring-fingers. The nippers thus in closing will shut down each on the adjacent ply of the blank, and they, for this purpose, are forked, as shown in Fig. 3, so that they may close on the blank without interfering with the opening-fingers c. Under this arrangement I am enabled to take hold of the mouth end of the blank at a point just in advance of the bite of the rolls.

I am aware that curved spring opening-fingers passing between and beyond the diamond-fold-forming rolls have been employed; but these fingers have been used in connection with ply-retaining devices which cannot take hold of the blank until its mouth-end has advanced a considerable distance beyond the rolls and the plies have been laid partly around the rolls, and for this reason, as well as for the further reason that it is necessary under such an ar-

rangement to get the fingers out of the way after they have performed their office as openers, said fingers have been arranged to reciprocate longitudinally. Under my improvement no reciprocation is needed. The fingers do not extend far enough forward to prevent the free passage of the blanks down around or partly around the lower roll; while by arranging the nippers as shown, and causing them to be seated when closed in the grooves *b*, I am enabled to take the blank just as it emerges from the bite of the rolls, and before its mouth, in fact, gets beyond the fingers. The diamond-folded blank *x* is fed along by the rolls *B* to the rolls *D E*, between which it passes. Roll *E* serves as the paste-roll, to deposit paste on parallel lines longitudinally of the diamond-fold in the usual way; and for this purpose it is provided with paste-ridges supplied with paste from a paste-trough and intermediate roll in the ordinary manner. The diamond-folded and pasted blank passes beyond the roll *E*, and has the second and third folds formed by the conjoint action of rolls *D F G* and vibratory tucker-blades *H I*. These instrumentalities for forming the second and third folds I do not here describe nor claim, inasmuch as I have made them the subject of a separate application for Letters Patent filed in the United States Patent Office on the 26th day of March, 1881.

It is sufficient to say that, as indicated in Fig. 1, a blind fold is formed in the body of the bag at the time the final fold is made by the conjoint action of the tucker *I* and the rolls *A G*. In order to straighten out the bag after it passes these rolls, I employ the following means, to wit: I place between the rolls and the endless apron *J* and endless traveling tapes *K* (which convey the bags to and around the drier and then discharge them from the machine) a curved guide and deflecting plate, *M*, as shown clearly in Fig. 1. The tapes are set some distance from the apron at the receiving end of the carrier, thus forming (as shown in the figure last referred to) a gradually-narrowing passage, *f*. As the bag passes the rolls *D G* its blind-folded part naturally

opens somewhat; and when the bag, in descending, reaches the angle of junction between the plate *M* and the apron it strikes that point along the line of its blind fold as seen in Fig. 1, and this naturally straightens out the bag a little more, throwing up at the same time its front end into contact with the tapes, which carry along that end in the gradually-narrowing passage *f* until the blank enters point first between the contact portions of the tapes and apron. Traveling along between these parts of the carrier it is straightened out and smoothed, dried, and finally discharged from the machine.

The tapes and apron, except in the particular above noted, are arranged in the usual manner, and are carried around the drier in the ordinary way; and these parts therefore require no further description.

Having described my invention, what I claim, and desire to secure by Letters Patent, is—

1. The peripherally-grooved rotating diamond-fold-forming rolls *A*, and the vibratory nippers *a*, carried by the same and operated to move at the times and in the manner specified, in combination with the spring opening fingers or strips *c*, extending in the peripheral grooves *b* and beyond the bite of the rolls, under the arrangement and for operation as herein specified.

2. In combination with the final-folding rolls, the carrier apron and tapes arranged so that there shall be formed at the receiving end of the carrier a gradually-narrowing passage, and the deflector or guide plate intermediate between the said apron and rolls, with its front end adjoining and below the level of the rear end of the carrier-apron, substantially as and for the purposes hereinbefore shown and described.

In testimony whereof I have hereunto set my hand this 14th day of June, A. D. 1881.
